UNITED STATES PATENT OFFICE.

CHARLES RADCLIFFE, OF NEWARK, NEW JERSEY.

BUTTON.

SPECIFICATION forming part of Letters Patent No. 289,138, dated November 27, 1883.

Application filed April 14, 1883. (No model.)

To all whom it may concern:

Be it known that I, CHARLES RADCLIFFE, a citizen of the United States, residing at Newark, in the county of Essex and State of New Jersey, have invented certain new and useful Improvements in Buttons; and I do hereby declare the following to be a full, clear, and exact description of the invention, such as will enable others skilled in the art to which it applies to make and use the same, reference being had to the accompanying drawings, and to letters of reference marked thereon, which form a part of this specification.

My invention relates to an improvement in buttons for use in sewing upon cloth and other material; and it consists in three plates, the two outer plates being provided with unobstructed central apertures and bent flanges around the edge to take hold of each other, while the central plate has a bar across the central aperture in it, affording a means for holding the thread, and is of a size to fit in between the other two plates and entirely fill the space between them diametrically and in thickness, but with sufficient liberty or looseness to allow of its being turned therein.

In the drawings, Figure 1 is a plan view of the improved button; Fig. 2, a plan view of the bottom plate; Fig. 3, a plan view of the top plate; Fig. 4, a plan of the central revolving plate or disk; and Fig. 5 is an enlarged section on line $\alpha\alpha$, Fig. 1.

Similar letters of reference indicate corresponding parts wherever they occur.

The top plate is lettered a and the bottom one b , and the central revolving plate or disk is lettered c . The central revolving plate is provided with a central opening having a cross-

bar, e . Both of the plates a and b are provided with unobstructed central openings coinciding with the opening in the disk c . The central opening in plate a is marked f , while that in plate b is marked g . The under plate, b , is provided with a turned-up flange around its edge, and the upper plate, a , is provided with a similarly-turned flange, h , which encompasses the flange on the lower plate and pinches upon and holds it. In putting the button together the plate or disk c is set in place in the plate b , and the plate a forced down upon them. As already explained, the disk c completely fills the space between the two plates a and b , and acts at one and the same time as a packing and as a center upon which the exterior plates, a , b , may revolve. The disk c , being united to the material or garment by thread passing over the bar e , will be held stationary, while the two outer plates are allowed to revolve over it when necessary.

What I desire to claim and secure by Letters Patent is—

A button composed of the two plates a and b , having unobstructed central openings and flanges on the edge, by which they are united, and a central revolving plate or disk, c , filling the entire space between the plates a and b , and adapted to revolve therein, and provided with a central aperture having the cross-bar e , substantially as set forth.

In testimony that I claim the foregoing I have hereunto set my hand this 28th day of March, 1883.

CHARLES RADCLIFFE.
